RAILWAY SIGNALING SYSTEM AND APPARATUS.

1,249,902.

Specification of Letters Patent.

Patented Dec. 11, 1917.

Application filed July 12, 1907. Serial No. 383,366.

To all whom it may concern:

Be it known that I, CLYDE J. COLEMAN, a citizen of the United States, and a resident of New York city, county of New York, State of New York, have invented certain new and useful Improvements in Railway Signaling Systems and Apparatus, of which the following is a specification.

My invention relates to an electric signaling system for railroads and involves a novel signaling system especially adaptable for use with railroads employing electric traction, while also including various specific features conduced to the more efficient and satisfactory operation of such systems.

I have shown my invention and have especially designed the same in connection with a system in which movable arms or semaphores are automatically operated to advise the engineer as to the condition of the track in the block or blocks that he is approaching. In making use of the terms signal and signaling system I do not intend to suggest that my invention is limited to this particular type of system but wish it to be considered that by such terms, which I have for purposes of simplicity used throughout this specification and throughout the claims, I include systems in which the automatic devices may operate alarms or set switches or act upon a train circuit or act upon any other apparatus in such a way as to automatically give warning to an operator or control the operation of the cars.

In all the best signaling systems thus far developed the signals have been in some way controlled by the passage of current in the track, such current being shunted by the wheels and axles of the car or train and being thus diverted from the electro-responsive devices that control the operation of the signals, the signals being thereby set to danger. My invention involves a signaling system in which this general method is followed. Where the railroads are operated by steam it has been the custom to cut the track into definite sections usually corresponding to the blocks of the signal system by inserting insulators between the rails at the end of each block. In this way the track is divided into a number of lengths, each supplied with current and each forming its own local circuit. When, however, electric trac-

tion is employed it is desirable to employ the rails to carry the traction current for one side of the circuit and to do this it is necessary that there shall be a continuous circuit for the traction current for a number of blocks through the track rails. Various means for permitting the free passage of the traction current, while providing means for properly operating the signals by means of a signaling current in the track rails, have been proposed but such systems have had important disadvantages either in the matter of cost of installation and operation or as regards reliability and efficiency or in failing to afford a wholly unobstructed conducting track circuit for the traction current, or in several of these respects combined. One feature of my present invention involves a means for properly confining the signal current to a given portion of the track while at the same time giving a low resistance track circuit through continuous rails for the traction current. The means that I have provided comprise cross bonds which connect the two rails of the track at intervals and have such a low resistance or impedance as to practically confine the current from any given source to the length of track from the said source to the nearest bonds. It is immaterial to my invention in its broader phase what character of source is employed or how it is arranged or connected with reference to the rails to supply current thereto. These bonds are preferably straight conductors of low resistance secured integrally to, or otherwise in good contact with, the two rails. These bonds are not only advantageous in confining each track signaling circuit, while permitting continuous rails to be employed for the traction current, but they are also advantageous in that they reduce the resistance of the track to the passage of the electric traction current by permitting transfer of current when for any reason the current has not equally divided between the rails. At the same time the provision of such bonds, with the source properly arranged and designed with reference to them, makes it unnecessary to introduce any insulators in the rails or provide any expensive impedance bonds or similar devices. Moreover, by limiting the circuit of each signal controlling current by means of these negli-

gible impedance bonds I am enabled to make a sharp line of demarcation between adjacent blocks so that, although using continuous rails, there will be no appreciable overlap and, therefore, on the one hand, there is no danger of the signal going to danger at times in the face of the engineer or, on the other hand, of the signal remaining at safety when the train has passed a substantial distance beyond the signal. In accordance with my invention the source of current which supplies the rails may supply them at any point between two succeeding bonds, while an electro-responsive device is arranged between the source and a bond so that it will receive current when there is no train between a given source and a given bond and the track is intact, while the current will be diverted from them when there is a train between such points.

Another feature of my invention involves the controlling of such electro-responsive devices by coils arranged in inductive relation to the track itself and this feature I prefer to use in connection with the employment of the bonds of negligible impedance. This feature of my invention involves the placing of a coil in inductive relation with one, or preferably, both rails of the track and at a distance from the point at which current is supplied to the track. This coil then acts as a secondary of a transformer, the rails themselves being the primary and the current supplied to said coil actuates a suitable relay controlling the local circuit of the signals. Whenever the train is adjacent to the point at which the current is supplied to the rails of the track, or whenever it is between said point and the said coil, the current is diverted from the rails so that there is no longer an inducing current in them and substantially no current will be produced in the coil. At such times the local signal circuit is opened and the signals go to danger. Preferably, but not necessarily, I connect the source of current to the track rails at about the center of a block, providing bonds of negligible impedance at the ends of the block and place a coil in inductive relation with the rails close to the end of the block. The current from this coil supplies a relay controlling the local signal circuit. With this arrangement the train must properly control the signal whatever be its position in the block because as soon as a pair of wheels have advanced far enough beyond the bond to have passed to a point where the diversion of the current from the rails will cause the transformer action to cease, the relay that receives current from the coil that is in inductive relation to the track at that point will be deenergized. There is, therefore, through the rails and the bond a complete circuit from the source and this circuit is complete independently of the

circuits of the signaling apparatus. The coil whose current determines the current to the signal controlling relays is in operative relation to the rails of the track where they are adjacent to the bond so as to receive a current whose value is determined by the current in such rails. On the other hand, the current in the bond includes also current from the source at the other side of the bond in another block and it is for this reason that the signal controlling relays are arranged to receive a current determined by the current in a rail rather than by that in the bond.

Since the relay receives its current from a coil by its operative relation to this definite short length of track it must necessarily be energized by but a minute portion of the energy supplied to the closed track circuit by the source. This employment of a relay energized by the current in a part of the track circuit having an impedance to the flow of signal controlling current not greater than that of a definite short length of rail is a feature of my invention which enables a practical continuous rail system to be provided having no overlap such as has always been necessary in previously proposed continuous rail systems in all of which the impedance of the portion of the track circuit which must be shunted by the train to produce the required deenergization of the relay has always been so high that it becomes substantially deenergized by a train a relatively long distance before it reaches said portion of the circuit.

Another feature of my invention, which I prefer to employ but which is not essential to the employment of the features of invention already described, comprises the operation of the switches or relays controlling the local circuit by means other than the current supplied from the track rails, while determining the time of the actuation of said relay by the flow of current in the track rails. This feature of invention also involves a novel construction and arrangement of relay to attain this mode of operation. This feature of my invention is advantageous since it permits a safe and reliable actuation of the local signal circuit by relatively feeble currents taken from the track rails.

These and other features of my invention will be set forth more fully hereinafter in the course of the detailed description of the specific embodiments I have illustrated. I will now describe these specific embodiments and will thereafter point out my invention in the claims.

Referring to the drawings Figure 1 illustrates diagrammatically a normal clear signal system embodying the various features of my system, while Fig. 2 is a more simple diagram illustrating the more important

features of my invention applied to operate home signals only.

It will be understood that it is immaterial to the employment of my invention whether 5 it is applied to a normal danger or a normal safety system or, indeed, whether the changing course of the current in the track rails, due to the passage of a train over the track, operates visible signals or operates some 10 other character of devices that are to be understood as being included by me when I refer to signals and signaling systems.

A, A' refer to rails of the railroad track. Each of the drawings shows a length of 15 track corresponding to two full blocks and portions of two other blocks. As indicated, the rails A, A' are electrically continuous throughout the portion of track shown and may be continuous for as many blocks as desired. The four blocks are numbered 1, 2, 3, 20 and 4. B, B', B² represent swinging semaphore arms placed at substantially the entrance to each block. These arms may be 25 of the ordinary construction of such arms, being arranged to have a gravity danger position except as controlled by electro-responsive devices acting upon them. Each of 30 these arms is to stand at the danger position when there is a train on the track in the block beyond the arm, or when there is any other condition that takes away the current from the electro-responsive devices governing the arm. C, C', C² are bonds connecting 35 the rails at intervals. In the present instance, these bonds correspond in number to the signaling arms. This is not an essential to my invention but it is an arrangement to be preferred. These bonds are of relatively low or negligible impedance. By this I 40 mean that they are of such a character as to afford so small an opposition to the flow of the signal controlling current that a current supplied to the rails at one side of such a bond will not pass beyond the bond in sufficient 45 quantity to have any practical effect upon the electro-responsive devices actuated by the changing flow of current in the track beyond the bond. Preferably the bonds are simply straight conducting bars of ample 50 cross-section and intimately connected with both rails. If the signal controlling current supplied to the track rails is an inductive current then to have the negligible impedance necessary the bonds should be of small ohmic 55 resistance and also of small inductance, while if the signal controlling current should be noninductive in character it would be immaterial whether such bonds have a high inductance or not since a high inductance 60 would have no effect upon impeding the flow of a noninductive current.

D is a prime source of signal controlling current which is in the present case assumed to be an alternating current dynamo.

65 So far I have only described elements

common to the two figures of the drawings accompanying the specification, but in order to complete the description of an operative system I will continue by first describing the more simple arrangement shown in Fig. 2 of 70 the drawings.

In this figure the circuit of the source D of signal controlling current supplies the primaries E, E' of transformers, these primaries being connected in parallel with each other. The secondaries F, F' of these transformers are connected at opposite ends to the two rails A, A'. The secondary F is connected to the rails at about the center of the block 2, while the secondary F' is connected to the rail at about the center of the block 3, it being understood that these form sources for the signal current in each block and that blocks 1 and 4 are likewise supplied with currents from similar transformers not shown. Taking the block 2 it will be noted that the current from the secondary F has two circuits, one to the left from one side of the transformer through the rail A, the bond C and the rail A', and the other at 80 the right of the transformer through the rail A, the bond C' and the rail A'. The bond C being of negligible impedance, as above set forth, will cause the difference of potential between the rails at the bond to be substantially zero, and this is equally true at the point at which the bond C' is provided. Whatever, therefore, the distance of the various sources from the bonds or from each other, and whatever the relative design and 90 capacities of such sources, the current from each source is confined within that part of the track included between the bonds on opposite sides of the source. The sources are shown connected directly to the rails but it 100 is not essential whether they supply the current to the rail in this way or through intermediate apparatus or inductively.

From each track source, therefore, there are two circuits, one on each side thereof. 110 Between adjacent sources there is always a well defined point of substantially zero difference of potential between the rails, which is fixed by the bond connecting them. When there is no train between sources there are 115 circuits through the track, which are complete independently of the apparatus constituting the signal controlling devices. The current employed for operating the latter is obtained by placing an electro-responsive 120 device in operative relation with this track circuit, and, preferably in inductive relation to the rails, at a point near the bond, so that the current taken by the electro-responsive device will have a value determined by the 125 electrical condition of that part of the track circuit.

G, G', G², etc., are coils placed in inductive relation to the rails of the track so as to produce a current when the signal controlling 130

current is flowing through the rails where adjacent to said coils. I prefer to place these coils at points adjacent to the bonds C, C', etc., being just far enough away from said bonds so that the bonds will not have a disturbing inductive effect upon the coils. The current from these coils G, G', G², is supplied to relays H, H', etc., which relays control the local signal circuit or the circuit 10 which directly acts upon the electro-magnets governing the movement of the semaphore arms. Thus in Fig. 2 each of these relays is indicated as a solenoidal coil which acts to draw down one end of a lever h, the other 15 end of said lever being weighted at h'. When there is current in the coil of the relay the arm h is in the position indicated in Fig. 2 for all the relays except H³. The semaphore arms B, B', B² are moved to safety position 20 when the electro-magnets J, J', J² are energized. The currents for energizing these coils are received from local sources which, in Fig. 2, are illustrated as batteries K, K', K². The relays in any given block control 25 the circuit from the battery to the magnet of that block, said relays being in series in such circuit.

Thus in the block 2 of Fig. 2 no train is supposed to be present. Under these circumstances, the current supplied by the secondary F passes through the rails to the bond C and thus produces a current inductively in the coil G', which current is supplied to the coil H' and maintains the switch controlled by that coil closed. In the same way the coil G² is supplying current to the coil H² and thereby holding the switch controlled by the latter coil closed. The current may therefore pass freely from 30 the battery K' through the electro-magnet J and thus hold the semaphore arm B at the position indicating a clear track. If either of the switches controlled by the coils H' and H² were opened the local signal circuit supplied by battery K' would be 35 opened and the semaphore arm B would go to danger.

It is a very important desideratum in all block signaling systems that the signal 40 should go to danger when there is a break in the track rail. It will be noted that my invention provides for this. Thus referring to block 2 of Fig. 2, which is indicated as clear, it will be seen that in order 45 to supply the current to both the coils H' and H² it is necessary that there should be at all points of the block a continuous rail conductor on each side of the track. Any break, therefore, that would render the circuit 50 on either side of the transformer F discontinuous would cause the opening of the local signal circuit and the movement of the semaphore arm B to danger.

When a train enters a block the situation 55 is that indicated in block 3 of Fig. 2. L, L

represent two axles of a train connecting the opposite track rails through the wheels. These wheels rest upon the track at points between the transformer F' and the bond C'. The circuit to the left of the transformer F' therefore includes these wheels and axles and that part of the rails to the left of these wheels is no longer supplied with signal controlling current from F'. The transformer action between the rails 70 and the coil G³ therefore ceases and no current is supplied by the coil G³ to the relay coil H³. The circuit from the battery K² to the magnet J' is therefore opened by the switch arm governed by the coil H³ and the 75 semaphore arm B' is set at danger. Before the axles L reach the points to which the secondary F' is connected to the rails the secondary will be so nearly short circuited as to reduce the current passing to the right 80 to bond C² to such a negligible quantity as to cause the coil G⁴ to no longer supply current to the relay H⁴, thus opening the same circuit at the switch governed by the relay coil H⁴. At this moment the circuit of the 85 coil J' will be opened at two points. A further advance of the train to a substantial distance past the secondary F' will cause the switch governed by H³ to close, but the switch governed by H⁴ will remain 90 opened until the last wheels of the train have substantially reached the bond C² at which time the forward wheels of the car or train will have passed the bond C² and caused the semaphore arm B² to be put to 95 danger.

While I have in the simple diagrammatic illustration of Fig. 2 shown the various preferred relations of the different devices constituting the system, yet it will be understood that in order to obtain the benefits of the bonds of negligible impedance and the coils inductively related to the track rails, or either of them, it is not essential that the various elements of the system be arranged 100 and connected precisely as indicated in this drawing.

In the foregoing description of the system as illustrated in Fig. 2 I have referred to the same without reference to the particular power used for the traction of the vehicle, but I have shown an arrangement which may be used whether the traction be electric or steam or of any other character, and if electric, whether it be direct current 115 or alternating current. It is to be understood that my invention may be employed with an inductive signal controlling current whatever the character of current employed for traction may be, provided the apparatus 120 is suitably designed and arranged and, so far as the bonds of negligible impedance are concerned, it is immaterial what character of current I employ for the signal controlling current.

Turning now to Fig. 1 of the drawings I have therein illustrated diagrammatically the details of a system employing a direct current power for electric traction and illustrating the application of my invention to a system employing both home and distant signals. I have also included in this figure features which I prefer to employ in connection with such a system.

10 The track rails A, A', the signals B, B', B², the bonds of negligible impedance C, C', C², the prime source of power for the signal controlling current D, the secondaries F, F', the coils G, G', etc., inductively related to 15 the rails, are all the same in Fig. 1 as in Fig. 2 and perform the same functions.

M is a source of electric power for the traction current, being indicated as a direct current generator, one terminal of which is 20 connected to the conductor 5, which may be, for example, a third rail, while the other is connected to the track rails. Conductor 5, in the present instance, also forms part of the circuit of the generator D supplying the 25 power for the signal controlling current. E², E³, E⁴ and E⁵ are primaries of series 30 transformers, these primaries being placed in the circuit of the source D. The secondaries of these transformers supply signal controlling current to the track rails, the secondaries F² and F⁵ being shown as connected directly to the rails as in the case of the transformers F and F', while the secondaries F³ and F⁴ are shown as supplying 35 current to the primaries E⁶ and E⁷ which are in inductive relation to the secondaries F and F'. It is immaterial whether the series 40 transformers supply the rails directly as in the case of the secondaries F² and F⁵, or indirectly as in the case of the secondaries F³ and F⁴. It is also immaterial to my invention whether or not series transformers are employed, the advantage of the series 45 arrangement being that it limits the flow of current in any one signal controlling circuit when it is short-circuited through the train.

The distant signals are represented by the semaphore arms N, N', N², which are of the usual type having a gravity danger position and moved to clear position when there 50 is current in the coils O, O', O².

In the case of Fig. 1 the coils G, G', etc., supply current to coils H⁶, H⁷, H⁸, H⁹, H¹⁰ and H¹¹, so that these coils, like the coils H 55 to H⁵ of Fig. 2, are supplied with current when the signal controlling circuit induces a current in the coils G, G', etc., but are not supplied with current when their respective coils G, G' are not producing current, because 60 of the passage of a train, or because of a broken rail, or because of the failure of the source or of a circuit forming part of the signaling system. The coils H⁶ to H¹¹, inclusive, magnetize members P of magnetizable material, which rest at one end upon

disks P', of magnetizable material. The members P move on bearings p and have a movement from a position engaging a contact p' to another position in which the connection between P and p' is broken. The former position is that occupied by five of the arms P of Fig. 1, while the latter position is that occupied by the arm in coöperation with the coil H¹¹. The disks P' are continuously 70 rotated by small alternating current induction motors Q, which are supplied with current from transformers Q' whose primaries are, in the present instance, in the circuit of the source D and in series with the primaries E² to E⁶. When there is no current 75 in any of the coils H⁶ to H¹¹, the lower end of the member P is moved to the right under the influence of the springs Q², as indicated in the case of the arm P that is in coöperation with the coil H¹¹. When, however, a 80 current is supplied to any of the coils H⁶ to H¹¹, as will be the case when the track is clear, the coil magnetizes its magnetizable member P and, therefore, the contacting surfaces of the arm P and the disk P'. Because 85 of the friction thus produced between these contacting surfaces the arm P is clutched and moved by the rotating disk P' to the position of engagement between P and p', thereby closing the local signal circuit. 90

The coils H⁶ to H¹¹ with the switch members P, the disks P' and the constantly rotating motors Q constitute relays controlled by the coils G to G⁵, the currents in the coils 100 of these relays determining the time of actuation of the relay, but not themselves giving the actuating power. The actual actuation of these relays is by means independent of the current in the coils H⁶ to H¹¹, that is by 105 the power of the motors Q. This enables the relays to be controlled by an extremely feeble current because such current does not need to be powerful enough to effect the actual movement of the switch. It is not 110 essential to the employment of my broad invention that this particular character of relay should be employed, but it has these features of advantage and may be employed not only in connection with other features 115 of my invention, but in any type of signal system.

In Fig. 1 the train L is shown in block 4 whereby current is shunted from the track circuit to the right of the coil G⁵ and therefore current is not induced in this coil nor supplied to the coil H¹¹. For this reason the relay controlled by the coil H¹¹ is open, the home and distant signals B² and N² are set at danger and the distant signal N' at 120 the entrance to the previous block is set at danger. On the other hand, the signals at the entrance to the block 2 are both at clear. I will now explain how these various results 125 are effected.

- The movement of the arms P of the relays indirectly control the coils J, J', J² of the home signals through special switches or relays R, R', R². The distant signals are controlled by the movement of the same switches R, R', R², such movement being governed in part by the relay arms P and in part by switches S, S', S² which are directly moved by the movement of the home signal, 10 being mechanically connected thereto. Each of the switches R, R', R² has a swinging switch member r having a central gravity position (see R²) and a position at each side of this gravity position (see R and R') 15 which the arm r takes according to whether the coil r' is in an active circuit or whether the coil r² is in such a circuit. In the gravity position, which is the position occupied by the member r of the switch R², the coils 20 r' and r² are connected respectively to a contact r³ at the left hand end of the switch and to a similar contact r⁴ at the right hand end of the switch through springs r⁵ and r⁶. When the switch is tilted so that 25 the left hand end is uppermost, the spring r⁵ is connected to one side (which I will hereinafter call the positive side for simplicity of explanation) through the contact r³ and the conductors connected therewith as 30 indicated. When the right hand end of the switch arm r is up, as shown at switch R', spring r⁶ is connected to "ground" through contact r⁴. 35 When the track is clear and in good order for the length of two blocks, the rocking switch assumes the position shown by the switch R. It is held in this position because current passes from conductor 5 to the contact r³ of switch R thence through the coil 40 r', thence through the conductor governed by the relays having coils H⁷ and H⁸, thence through the switch S' mechanically connected to the home signal B' of the next block, and thence to ground. With the switch in 45 this position there is a circuit from the conductor 5 directly through the coil J controlling the home signal B and thence through the fixed contact r⁸ and contact r⁴ to ground. At the same time the coil O, controlling the 50 distant signal N, is energized, the current passing from conductor 5 through contacts r³, r⁷ through coil O, contact r⁸ and contact r⁴ to "ground". When there is a train in the block governed by the signals the switch 55 member r assumes the gravity position, as indicated by switch R². The train L in block 4 has shunted the current that would pass through the rails in that block and the bond C² so that the coil G⁵ is not supplying 60 current to the coil H¹¹. The relay arm P governed by the coil H¹¹ has therefore been moved to the open position by its spring Q² and the circuit of the coils r', r² of switch R² has been opened at that point. As there 65 is current in neither of these coils the member r of the switch R² takes the gravity position and, therefore, contacts with neither of the fixed contacts r⁷, r⁸, r⁹. Under these circumstances the circuit to the coil J², controlling the home signal, is broken at the 70 ground side, while the circuit to the coil O², controlling the distant signal, is broken at both sides. The home and distant signals B² and N² are therefore set at danger, as indicated. The movement of the home signal 75 B² moves the switch S² thus connecting the conductor 5 through the contacts governed by coils H⁹, H¹⁰ with the coils r', r², governing the switch member R'. This causes a current to pass from conductor 5 through 80 coils r², contacts r⁶ and r⁴ to the ground side of this circuit, energizing coil r² and tilting the arm r of switch R' to the position shown. By this movement of the switch the current 85 can pass through the coil J' directly controlling the home signal B', a ground connection for said coil being completed through the contact r⁹ and contact r⁴ of switch R'. 90 It is obvious that various modifications may be made in the constructions and arrangements which I have particularly described within the principle and scope of my invention as severally set out in the following claims. 95 Having thus described my invention, what I claim as new and desire to protect by Letters Patent is: 1. In a block signaling system, a conductively continuous track, bonds of negligible impedance connecting the rails of the track at the ends of a block, means for supplying current to the rails intermediate the block ends, and electro-responsive devices arranged to affect the operation of the signals and controlled in accordance with the flow of current in said rails. 100 2. In a railway block signaling system employing the opposite track rails as conductors of opposite polarity in a signal controlling circuit, bonds of negligible impedance connecting the rails of the track at substantially the ends of each block. 110 3. A means for confining the flow of a signal controlling current within a definite portion of a railway track, comprising bonds of negligible impedance connecting the rails at each end of the track portion in which the current is to be confined. 115 4. In a railway signaling system, a conductively continuous track, bonds of negligible impedance connecting the rails at intervals, sources of signal controlling current connected to the rails intermediate said bonds, and electro-responsive devices arranged to affect the operation of the signals and controlled in accordance with the flow of current in the rails between said sources and said bonds. 120 5. In a railway signaling system, a con- 125

- ductively continuous track, bonds of negligible impedance connecting the rails at intervals, sources of current arranged to produce a difference of potential between the 5 two rails at points intermediate said bonds, and signal controlling electro-responsive devices connected and arranged to be actuated by the current flowing from said sources to said bonds.
- 10 6. In a railway signaling system, a conductively continuous track, bonds of negligible impedance connecting the rails at intervals, a source of signal controlling current connected to the rails intermediate each 15 adjacent pair of bonds, and electro-responsive devices arranged to affect the operation of the signals and controlled in accordance with the flow of current in the rails between said sources and said bonds.
- 20 7. In a railway signaling system, a conductively continuous track, bonds of negligible impedance connecting the rails at intervals, sources of signal controlling current connected to the rails intermediate said 25 bonds, signal controlling devices, and electro-responsive devices for governing the same connected and arranged to be actuated in one direction or the other according to whether or not the current from the source 30 is diverted from the rails between a source and one of said bonds.
8. In a railway signaling system, a block formed by the rails of the track and low impedance bonds connecting said rails, a source 35 of current supply connected to the rails and having signal controlling circuits each through one rail, a bond and thence through the other rail, and electro-responsive signal controlling devices energized responsively 40 to the flow of current in said circuits.
9. In a railway signaling system, means for supplying an electric current to the rails of the track, a coil in inductive relation to said rails, a signal, and means for actuating 45 said signal responsively to current changes in said coil.
10. In a railway signaling system, means for supplying an electric current to the rails of the track, a coil arranged with its sides 50 in inductive relation with the opposite rails of the track, a signal, and means for actuating said signal responsively to current changes in said coil.
11. In a railway signaling system, a source 55 of electric supply, a circuit supplied thereby including track rails, said circuit being so connected to the source and arranged that the current is in opposite direction in the two rails, a coil in inductive relation with 60 both rails, a signal, and means for actuating said signal responsively to current changes in said coil.
12. In a railway signaling system, the track rails, a source of supply having one of 65 its poles connected to each rail, a bond of negligible impedance connecting the rails, a coil in inductive relation to the rails at a point intermediate the source and the bond, a signal, and means for influencing the same responsively to current changes in said coil. 70
13. In a railway signaling system, the track rails, a source of supply having one of its poles connected to each rail, a low impedance bond connecting the rails, a coil in electrical coöperation with the rails at 75 a point intermediate the source and the bond, a signal, and means for influencing the same responsively to current changes in said coil.
14. In a railway signaling system, the 80 track rails and two bonds of low impedance connecting them, a source of current supply intermediate the bonds with one pole connected to each rail, two coils in electrical coöperation with said rails at points between 85 the source and the bonds, a signal, and means for actuating the same upon a given decrease of current in either coil.
15. In a railway signaling system, the track rails and two bonds of low impedance 90 connecting them, a source of current supply intermediate the bonds with one pole connected to each rail, two coils inductively related to said rails at points between the source and the bonds, a signal, and means 95 for actuating the same upon a given decrease of current in either coil.
16. In a railway track signaling system, conductively continuous track rails, bonds of negligible impedance connecting the rails 100 at intervals, sources of current supply connected to the rails between each pair of bonds, a coil in electrical coöperation with the rails between each source and each bond, signals, and means for actuating each of the 105 same upon a given decrease of current in either of the coils between a given pair of said bonds.
17. In a railway track signaling system, conductively continuous track rails, bonds of negligible impedance connecting the rails at 110 intervals, sources of current supply connected to the rails between each pair of bonds, a coil inductively related to the rails between each source and each bond, signals, and means for actuating each of the same 115 upon a given decrease of current in either of the coils between a given pair of said bonds.
18. In a railway signaling system, the 120 rails of the track, a bond of negligible impedance connecting them, a source of electric supply delivering current to the rails at a substantial distance from said bond, and a coil adjacent to the bond and inductively related to said track rails. 125
19. In a railway signaling system, the track rails, a bond of negligible impedance connecting them, a source of electric supply connected to the track rails at a substantial 130

distance from the bond, a coil inductively related to the rails adjacent to the bond, a relay controlled by the current in said coil, and a signaling circuit controlled by said 5 relay.

20. In a railway signaling system, the track rails, a bond of negligible impedance connecting them, a source of electric supply delivering current to the track rails at 10 a substantial distance from the bond, a coil receiving current responsively to current variations at given points in the rail circuit, a switch, means for determining the actuation of said switch in accordance with the 15 current in said coil and for actuating the switch by means independent of the current in said coil, and a signal circuit controlled by the movement of said switch.

21. In a railway signaling system, the 20 track rails, a bond of negligible impedance connecting them, a source of electric supply connected to the track rails at a substantial distance from the bond, a coil in inductive relation to the rails of the track between the 25 source and the bond, a circuit supplied by said coil, a signal circuit, and a switch controlling the same, means dependent upon the current in the circuit supplied by said coil for determining the actuation of said switch, 30 and means independent of said current for actuating the switch.

22. In a railway signaling system, a source of electric power, a circuit supplied thereby, part of which includes a length of 35 the track rails and a bond of low impedance connecting the same, and an electro-responsive signal controlling device in operative relation with a track rail adjacent to said bond.

40. 23. In a railway signaling system, a source of electric power, a circuit supplied thereby, part of which includes a length of the track rails and a bond of negligible impedance connecting the same, and an electro-responsive signal controlling device energized when there is a flow of current through 45 said bond and length of rails.

24. In a railway signaling system a length of track rails and a conducting bond connecting them, and an electro-responsive signal controlling device in operative relation with a track rail adjacent to said bond.

25. In a railway signaling system a length of track rails and a bond of negligible impedance connecting them, and an electro-responsive signal controlling device energized by the flow of current through said rails and bond.

60. 26. In a railway signaling system, a block formed by the rails of the track and conducting bonds connecting said rails, a source of current supply connected to the rails and forming circuit each through one rail, a bond and thence through the other rail, and 65 electro-responsive signal controlling devices

energized responsively to the flow of current in a given portion of the rail of said circuit.

27. In a railway signaling system, a signal controlling circuit, a coil supplied with 70 current thereby, a switch, means for determining the actuation of said switch in accordance with the current in said coil, independent means for actuating said switch and a signal circuit controlled by the move- 75 ment of said switch.

28. In a railway signaling system, the combination of the track rails, a source of signal controlling current supply in operative relation therewith, a bond connecting 80 the rails and completing the track circuit, a coil in operative relation with one of said rails adjacent to said bond and between the same and said source, a signal, and means for controlling the same according to the 85 flow of current in said coil.

29. In a railway signaling system, two sources of signal controlling current, a pair of conductively continuous rails supplied thereby at different points, and a bond connecting 90 the rails at a point between said sources and completing the circuits from the respective sources.

30. In a railway signaling system, two sources of signal controlling current, a pair of conductively continuous rails supplied thereby at different points, a bond connecting the rails at a point between said sources and completing the circuits from the respective sources, and electro-responsive 100 devices, in operative relation one with each of said circuits.

31. In a railway signaling system, two sources of signal controlling current, a pair of conductively continuous rails supplied 105 thereby at different points, a bond connecting the rails at a point between said sources and completing the circuits from the respective sources, and electro-responsive devices, one in operative relation to a track 110 rail where adjacent to said bond and the other in operative relation to a track rail where adjacent to said bond but on the opposite side thereof.

32. The combination in a signaling system for electric railways, of a power circuit for propelling the cars of which the two traffic rails form a part and are continuous, closed track circuits, a source of signaling energy fed to the rails of each track circuit, 120 and a translating device operatively related to the traffic rails for controlling a signal, a cross-bond between the rails, a circuit in inductive relation with the rails and a translating device in the last mentioned circuit. 125

33. In a railway signaling system, a track having conductively continuous rails, sources of signal controlling current supplying the same at intervals, there being between each pair of adjacent sources a place in the track 130

5 circuit of normally substantially zero difference of potential of the current of said sources from one side to the other, electro-responsive devices in operative relation to the track circuits at points between each of said zero points and each source, and signals operatively related to said electro-responsive devices.

34. In a railway signaling system, a track 10 having conductively continuous rails, sources of signal controlling current supplying the same at intervals, there being between each pair of adjacent sources a place in the track circuit of normally substantially zero difference of potential of the current of said sources from one side to the other, electro-responsive devices in operative relation to the track circuit at points relatively near and at each side of said zero points, and 15 signals operatively related to said electro-responsive devices.

35. In a railway signaling system, a track having conductively continuous rails, sources of signal controlling current supplying the same at intervals, means for producing a normally substantially zero difference of potential for each pair of adjacent sources at a place in the track circuit between said sources, and signal controlling electro-responsive devices operatively related to the track circuit at points between each source and each of said zero places.

36. In a railway signaling system, a track having conductively continuous rails, sources 35 of signal controlling current supplying the same at intervals, means for producing a normally substantially zero difference of potential for each pair of adjacent sources at a place between said sources, and signal controlling electro-responsive devices operatively related to the track circuit at points at each side of and relatively near said zero points.

37. In a railway signaling system, conductively continuous track rails, a source of signal current supply operatively related thereto, and a bond connecting the rails and forming a definite point of substantially zero difference of potential for the track circuit supplied by said source.

38. In a railway signaling system, conductively continuous track rails, a source of signal current supply operatively related thereto, a bond connecting the rails and causing substantial zero difference of potential between the rails at a definite location in the track circuit supplied, and an electro-responsive signal controlling device in operative relation to the rail circuit at a point 55 relatively near the bond.

39. In an electric railway system, conductively continuous track rails, a source of power current having one side connected to the rails, sources of signal controlling current supplying a difference of potential to

the rails at intervals, means for producing points of normally zero difference of potential at a place between each adjacent pair of sources of signal controlling current for the current from said sources, and an electro-responsive device in operative relation with the track between each source of signal controlling current and each said zero place.

40. In an electric railway system, conductively continuous track rails, a source of power current having one side connected to the rails, sources of signal controlling current supplying a difference of potential to the rails at intervals, negligible impedance bonds connecting the rails between sources of signal controlling current, and an electro-responsive device in operative relation with the track at each side of and relatively near each bond.

41. In an electric railway system, conductively continuous track rails, a source of power current having one side connected to the rails, sources of signal controlling current supplying a difference of potential to the rails at intervals, negligible impedance bonds connecting the rails between sources of signal controlling current, and an electro-responsive device in operative relation with a localized portion of the track at each side of and relatively near each bond.

42. In an electric railway system, conductively continuous track rails, a source of power current having one side connected to the rails, sources of signal controlling current supplying a difference of potential to the rails at intervals, negligible impedance bonds connecting the rails between sources of signal controlling current, an electro-responsive device in operative relation with the track at each side of and relatively near each bond, and signals each in operative relation with the electro-responsive devices between successive bonds.

43. In an electric railway system, conductively continuous track rails, a source of power current having one side connected to the rails, an alternating current source, transformers supplied thereby having their secondaries connected across the rails at intervals, means for providing normally substantially zero difference of potential between the rails at a point between each pair of successive secondaries, an electro-responsive device in operative relation to the track between each of said zero points and said 115 transformers, and signals in operative relation to said electro-responsive devices.

44. In an electric railway system, conductively continuous track rails, a source of power current having one side connected to the rails, an alternating current source, transformers supplied thereby having their secondaries connected across the rails at intervals, means for producing normally substantially zero difference of potential be- 125 130

tween the rails at a point between each pair of successive secondaries, an electro-responsive device in operative relation to the track at each side of and relatively near each of 5 said zero points, and signals in operative relation to said electro-responsive devices.

45. In an electric railway system, conductively continuous track rails, a source of power current having one side connected to 10 the rails, an alternating current source, transformers supplied thereby having their secondaries connected across the rails at intervals, a low impedance bond connecting the rails at a point between each pair of 15 successive secondaries, an electro-responsive device in operative relation to the track between each bond and transformer, and signals in operative relation to said electro-responsive devices.

20 46. In an electric railway system, conductively continuous track rails, a source of power current having one side connected to the rails, an alternating current source, transformers supplied thereby having their 25 secondaries connected across the rails at intervals, a low impedance bond connecting the rails at a point between each pair of successive secondaries, an electro-responsive device in operative relation to the track at 30 each side of and relatively near each bond, and signals in operative relation to said electro-responsive devices.

47. In an electric railway system, conductively continuous track rails, a source of 35 power current having one side connected to the rails, an alternating current source, transformers supplied thereby having their secondaries connected across the rails at intervals, a low impedance bond connecting 40 the rails at a point between each pair of successive secondaries, an electro-responsive device in inductive relation to the track at each side of and relatively near each bond, and signals in operative relation to said 45 electro-responsive devices.

48. In an electric railway system, a source of power current, conductively continuous rails electrically connected by low impedance bonds at intervals and together constituting 50 one side of the power circuit, means for supplying an alternating current difference of potential to the rails between successive bonds, electro-responsive devices in operative relation with the track between 55 successive bonds, and signals in operative relation with said electro-responsive devices.

49. In an electric railway system, a source of power current, conductively continuous rails electrically connected by low impedance bonds at intervals and together constituting 60 one side of the power circuit, means for supplying an alternating current difference of potential to the rails between successive bonds, electro-responsive devices in 65 operative relation with a definite section of

the track between successive bonds, and signals in operative relation with said electro-responsive devices.

50. In an electric railway system, a source of power current, conductively continuous 70 rails electrically connected by low impedance bonds at intervals and together constituting one side of the power circuit, means for supplying an alternating current difference of potential to the rails between successive 75 bonds, electro-responsive devices in operative relation with the track each at a point relatively near one of the bonds, and signals in operative relation with said electro-responsive devices. 80

51. In an electric railway system, a source of power current, conductively continuous rails electrically connected by low impedance bonds at intervals and together constituting one side of the power circuit, means for supplying an alternating current difference of potential to the rails between successive 85 bonds, electro-responsive devices in operative relation with a definite section of the track each at a point relatively near one of the bonds, and signals in operative relation with said electro-responsive devices. 90

52. In an electric railway system, a source of power current, conductively continuous rails electrically connected by low impedance 95 bonds at intervals and together constituting one side of the power circuit, means for supplying an alternating current difference of potential to the rails between successive bonds, electro-responsive devices in inductive 100 relation with the track each at a point relatively near one of the bonds, and signals in operative relation with said electro-responsive devices.

53. In a railway signaling system, a signal, an electro-responsive device in operative relation therewith, a transformer having a track rail and a coil in inductive relation to each other, and a source of inducing current, one of the elements of said transformer 110 being supplied by said source and the other supplying said electro-responsive device. 105

54. In a railway signaling system, the track rails, an electro-responsive device in operative relation with the same, a source 115 of alternating current supply, and a transformer intermediate said source and said electro-responsive device, one element of said transformer including a rail of the track.

55. In a signaling system, a trackway in 120 which the rails are electrically continuous and divided into block sections by cross bonds.

56. In a signaling system, a trackway the rails of which are electrically continuous and 125 divided into a series of closed track circuits through the instrumentality of cross bonds.

57. In a signaling system, a trackway, the rails of which are electrically continuous, a series of cross bonds dividing the rails into 130

block sections, means for impressing an alternating current in each track circuit and means normally energized by said impressed current and adapted to control a signal or signals.

5. 58. In a railway block signaling system a closed track circuit and a source of signaling current supplying the same, a signal, a signal controlling electro-responsive devices, and means for operating the same to set the signal responsive to a movement of a vehicle over a short portion of the rails at the end of the block, said means deriving its energy from a portion of said track circuit 10 having an impedance to said signaling current of the order of magnitude of the short portion of the rails over which the vehicle must move to set the signal.

20. 59. In a block signaling system for electric railways, a track circuit including a source of alternating current supplying the same at one end thereof and having a portion at the other end thereof whose impedance is of the same order of magnitude as 25 that of a certain short length of the track rail of the circuit, said short length being located at the latter end of the circuit and being approximately thirty-two feet of rail, and electro-responsive apparatus operatively 30 related to said portion of the circuit to receive its operating energy therefrom and be effectively controlled by said energy.

25. 60. In a railway signaling system conductively continuous rails, sources of signaling current feeding the rails, electromagnetic devices, signals controlled thereby, and means coöperating with stretches of the rails for energizing said electromagnetic devices, the energy thus delivered to said devices be-

ing proportional to the length of said 40 stretches and said stretches being of a length sufficient to effectively energize said devices when the normal degree of energy from said sources is present in said stretches.

45. 61. In a railway signaling system, conductively continuous rails, sources of signaling current feeding the rails, electro-responsive devices controlled thereby and means coöperating with stretches of the rails for energizing said electro-responsive devices, 50 the energy thus delivered to said devices being proportional to the length of said stretches, and said stretches being of a length sufficient to effectively energize said devices when the normal degree of energy 55 from said sources is present in said stretches.

62. In a railway block signaling system, a source of signal controlling current, a track circuit the rails of which include a 60 long stretch supplied at one end by the source and a short stretch connected to the other end of the long stretch, and electro-responsive signal controlling means coöperating with said short stretch and effectively 65 energized when current from said source flows throughout said short stretch, the energization decreasing substantially proportionately as said short stretch of rail is progressively short-circuited by a passing 70 train.

In testimony whereof, I have signed my name to this specification, in the presence of two subscribing witnesses.

CLYDE J. COLEMAN.
